UNITED STATES PATENT OFFICE.

THOMAS DAVIS AND CHARLES E. DAVIS, OF INDIANAPOLIS, INDIANA.

ICE-MACHINE AND REFRIGERATING APPARATUS.

SPECIFICATION forming part of Letters Patent No. 252,021, dated January 10, 1882.

Application filed November 7, 1881. (No model.)

To all whom it may concern:

Be it known that we, THOMAS DAVIS and CHARLES E. DAVIS, residents of Indianapolis, in the county of Marion and State of Indiana, have invented a new and useful Improvement 5 in Ice-Machines and Refrigerating Apparatus, of which the following is a specification, having reference to the accompanying drawings.

Our invention relates to that class of refrigerating apparatus in which aqua-ammonia is distilled and the product of distillation condensed by pressure, and the removal of its sensible heat to a liquid, which liquid, upon being released from pressure, assumes the 10 gaseous form, and after circulating through a system of pipes is reconverted into aqua-ammonia and conveyed back to the retort to be redistilled, and thus continuously circulates so long as heat is applied to the retort or boiler.

20 The object of our invention is, first, to utilize the refrigerating power of the ammonia when passing from the liquid to the gaseous state to reduce the liquid product of distillation to the lowest possible temperature just before its

25 liberation from pressure; second, to easily and cheaply reduce the temperature of the weak liquor remaining, after the separation of the ammonia, to a degree which will fit it to rapidly reabsorb the ammonia and hold it strongly

30 in solution, so that the resulting re-formed aqua-ammonia can be returned to the boiler or retort by means of an injector.

The accompanying drawings illustrate my invention, in which Figure 1 is a general elevation, the boiler and tanks being shown in section. Fig. 2 is a partial plan, as hereinafter described.

35 In Fig. 1, A is a retort or boiler, constructed of iron and of sufficient strength to sustain a pressure of two hundred and twenty pounds to the square inch.

40 B is a steam-heater, placed within the boiler A and connected with a steam-generator by the pipe H, and provided with a blow-off pipe and valve, b.

45 J is a pipe leading from the top of boiler A, which, passing through the condensing-tank C, forms therein the coil K.

E is refrigeratory chamber, built of wood or 50 other non-conductor of heat. A continuation of the pipe J from the coil K passes into the

chamber E, and there forms the coil L, the end of which is closed by the valve d.

Connected to the valve d is a pipe, M, which traverses the chamber E above the coil L, and 55 passing out at a enters the closed chamber F. Chamber F is strongly made of iron and is air-tight. The pipe M traverses the chamber F, near the bottom thereof, as shown at N, and passes out at c into the distributor O. From 60 O the distributing-pipes P P P P form coils in the refrigeratory tank G, terminating in the receiver Q, which is connected with the chamber F by the pipe R. A pipe, S, enters the boiler A near the bottom, below the heater B, 65 and passing upward enters the cooling-tank D, in which it forms the coil T, and passing out near the bottom of the tank, at U, enters the closed chamber F, in which it rises to near the top. The pipe V leads from the bottom of 70 the chamber F to the injector W, which is inserted in the side of boiler A, as shown, and is also connected therewith by the pipe X. A pipe, Y, leads from near the discharge of the injector W into the closed chamber Z.

75 The operation of our device is as follows: Into the boiler A, a quantity of strong aqua-ammonia is put, sufficient to fill it to about the dotted line e e and submerging the heater B. The tanks C and D are now filled with cold water from the supply-pipe f, the water overflowing at l and m, and being constantly replaced. The refrigerating-tank G is filled with a strong brine. The stop-valves in all the pipes leading from A being closed, steam is now admitted to the heater B, raising thereby the temperature of the aqua-ammonia and expelling the ammonia therefrom in a gaseous form. When the pressure of the ammonia within the boiler A has reached one hundred and fifty 80 pounds to the square inch, or thereabout, as indicated by the gage k, the valve h in pipe S is opened and the denser portion of the water from which the ammonia has been expelled in boiler A passes from the bottom of A, below 85 the heater B, into the coil T in the cooling-tank D, where it is deprived of a large portion of its heat. It then passes into the closed chamber F until said chamber is nearly filled, the air passing out at the open purge-cock a². The 90 valve r in pipe J is now opened, and the ammonia passing into the coil K in the condenser 95 and valve d is closed. The ammonia then passes into the coil L in the chamber E, and is 100 returned to the boiler A by the pipe J.

C is condensed to a liquid by the combined action of the pressure from A and the lowering of its temperature by the water in C. It is at this point that our invention is introduced.

5 In this class of refrigerators the boiler A, heater B, cooling-tanks C and D, coils K and T, and their connections with boiler A, and the refrigerator-tank G, with its system of distributing-pipes, are all old and well-known devices; but as heretofore constructed and arranged the ammonia, after leaving the condenser C, passes through a continuation of the pipe in which it is contained when leaving condenser C directly through the valve *d* to the distributor O, connected with the system of distributing-pipes in G.

The first part of our invention consists in inclosing together in a chamber, E, formed of non-heat-conducting material, a portion of the 20 pipe conveying the liquefied ammonia while under great pressure, forming the coil L, and another portion of pipe M conveying the ammonia when relieved from such pressure. The result produced is a further reduction of the 25 temperature of the liquid in the coil L while still under great pressure, and the consequent greater expansion and increase of refrigerative power in the ammonia when released from pressure in pipe M. The well-known property 30 of ammonia, when passing from a liquid to a gaseous form, of absorbing sensible heat and changing it to latent heat, prevents any perceptible rise in temperature in the ammonia in the pipe M from the heat absorbed from the 35 coil L.

The second part of our invention consists in the means employed for reducing the temperature of the weak liquor taken from the boiler A after the expulsion of its ammonia, and thus 40 fitting it to absorb the ammonia after it has passed through the refrigerator. In this class of refrigerating apparatus, as heretofore constructed, this result has been attained in some cases by causing cold water to circulate in a 45 coil through a considerable mass of the weak liquor, and in others by surrounding the chamber containing the liquor by a water-jacket in which a circulation of cold water is kept up. By this means of cooling the weak liquor in the 50 absorber it has been found difficult to keep down its temperature to that point which will best fit it to absorb and retain the ammonia, the result being that the absorption is feeble and slow, and the slight hold which the imperfectly- 55 cooled liquor has upon the ammonia renders ordinary pumps or injectors inoperative, and thus requires complicated and expensive pumping machinery to return the liquor to the boiler.

Our improvement consists in placing the absorption-tank F, containing a small amount of weak liquor, between the chamber E and the refrigerator-tank G, and passing through it the pipe M, containing the expanding ammonia on its way to the refrigerator G. We are thus

enabled to produce a much lower temperature 65 in the liquor than has before been possible with the means employed, and as a result the ammonia, after passing through the system of pipes P, and returning to the absorber F through the open pipe R, is rapidly absorbed. The re-formed aqua-ammonia thus produced is drained off by the pipe V and returned to the boiler by the injector W, which is operated by a jet of ammonia from the upper part of A through the pipe X. The aqua-ammonia thus removed is replaced by fresh weak liquor from the boiler, and the stop-valves in the several pipes being properly adjusted, the process goes on continuously. In first starting the injector it is necessary to allow the jet of ammonia to flow 80 through without entering the boiler.

To prevent the loss of ammonia we have provided the waste-pipe Y, which connects the blow-off cock *b*² with a closed receiver, Z, in which the ammonia is received and absorbed 85 by water placed therein, which is afterward drained off through the cock *c*².

We claim as our invention—

1. In an ammonial refrigerating apparatus, the combination of the coil L and pipe M, having their interiors separably connected by a valve, *d*, and the chamber E inclosing both, substantially as described, and for the purpose set forth.

2. In an ammonial refrigerating apparatus, 95 the combination of the absorption chamber F with the pipe N, conveying ammonia to the distributing-pipes P, and pipe R, conveying ammonia from the distributing-pipes P, substantially in the manner and for the purpose set 100 forth.

3. In an ammonial refrigerating apparatus, the combination of the above-described chamber E, inclosing the coil L and pipe M, with the condensing-tank C, coil K, and system of distributing-pipes P, for the purpose set forth.

4. In an ammonial refrigerating apparatus, the combination of the absorption-chamber F, having pipes N and R, in the manner above described, with the supply-pipe U, coil T, and cooling-tank D, for the purpose set forth.

5. In an ammonial refrigerating apparatus, the combination of the absorption-chamber F, provided with pipes N and R, in the manner above described, with the connecting-pipe V, 115 injector W, and boiler A, for the purpose set forth.

6. In combination with the injector W, the pipe Y and closed overflow-receiver Z, substantially as described, for the purpose set forth.

In testimony whereof we have hereunto signed our names.

THOMAS DAVIS.
